MOLDING STRIP

David R. Holls, Detroit, Mich., assignor to General Motors Corporation, Detroit, Mich., a corporation of Delaware

Application January 7, 1955, Serial No. 33,870

Term of patent 7 years

(Cl. D14—6)

Fig. 1 is a side elevational view of a molding strip embodying my new design;

Fig. 2 is an enlarged elevation of the molding strip, portions of the strip intermediate its ends being broken away; and

Figs. 3, 4, 5 and 6 are transverse sections through the molding strip taken, respectively, along the lines 3-3, 4-4, 5-5 and 6-6 of Fig. 2.

The disclosure of an automobile by means of broken lines is shown only for the purpose of illustration.

I claim:

The ornamental design for a molding strip, substantially as shown and described.
